UNITED STATES PATENT OFFICE.

EDWARD E. CLEMENT, OF WASHINGTON, DISTRICT OF COLUMBIA, ASSIGNOR, BY
MESNE ASSIGNMENTS, TO FREDERICK C. STEVENS, OF ATTICA, NEW YORK.

TELEPHONE-EXCHANGE SYSTEM.

1,107,134.

Specification of Letters Patent. Patented Aug. 11, 1914.

Application filed March 27, 1905. Serial No. 252,307.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawing.

10 My invention relates to telephone exchange systems, and has for its object the production of improved means of ringing or signaling a wanted subscriber.

Stated in a word the invention is a scheme 15 for automatic ringing, but it is an improvement over the ordinary automatic, in that the calling subscriber may have control of the ringing key after the operator has once rung, and may repeat the ring as often as he 20 desires until the wanted subscriber answers after which he cannot ring, but at all times can call the operator, or make a "recall".

In one embodiment of the invention I give the control of the ringing after the operator 25 has set the connection up, to a mechanical device which if not impeded will ring at periodical and predetermined intervals. After the called subscriber has answered, however, neither this machine nor the calling 30 subscriber, or for that matter the operator, can affect the ringing relay.

My invention is fully illustrated in the accompanying drawings, wherein—

Figure 1 is a diagram showing the scheme 35 applied to a two wire common battery cord circuit, the line jacks being three-wire; Fig. 2 is a diagram showing the invention applied to party line selective ringing; and Fig. 3 is a diagram similar to Fig. 1 showing modified 40 means for controlling the battery supply.

In the drawings, and referring first to Fig. 1, A and A' are two subscribers' stations, each equipped with the usual telephone outfit and ringer, adapted to work in a common battery system. Each line 1—2 or 3—4 terminates in a jack at central, J or J', to the thimble of which the cut-off relay N is connected and to ground. The cord circuit includes the plugs P and P', connected by conductors 5—6, 7—8, separated by condensers as customary. In a bridge 9—11—14—15 across the answering end of the cord are connected the relays S, S² and the main battery B. In a similar bridge 10—12—14 50 across the calling end of the cord are connected the relays S', S³ and the main battery B. Relays S² and S³ close the battery onto the contacts of the relays S and S' when the respective plugs are inserted in jacks; and relays S and S' close the circuits of the supervisory lamps s and s' when they are deenergized, being furnished with back contacts for the purpose. As the battery B is connected by its free pole to the sleeve side of the cord and so to line, the cut-off relay N gets current when any plug goes in, being then in series with the relay S² or S³ as the case may be.

All the above is old and not described as a part of my invention except as it must be included for completeness in operation. The circuit I have set forth and illustrated, moreover, may be varied at will without affecting my improvements, which I will now point out particularly.

From the tip and sleeve of the plug P' the 75 respective strands pass as usual to a ringing key, but instead of a mechanical key I show a magnetic key or relay, K. The armatures of this relay, k' and k², normally complete the 80 cord and disconnect the generator circuit. The magnet of this relay has its winding included in a branch taken off from the back contact of the called subscriber's supervisory relay, S', the circuit being from said back 85 contact by wire 19 to the back contact of a disabling relay S⁴, thence by wire 190 to relay K, and thence to ground by one of three paths. The first path is through the operator's ringing button K⁰, the second through 90 the wire 22 and switch m' to the constantly revolving commutator K⁶ which first puts ground on the wire 22 for three seconds and then takes it off for the same length of time, and the third through the wire 22 to switch 95 m and by wire 20 to the back contact of the calling supervisory relay S. It should be stated here that the relay K is made very sluggish, so that it takes an appreciable length of time to pull in its armatures. This 100 may be attained by either putting a copper ring on its poles, by giving it a wide air gap and a poor magnetic circuit, or by other means well known to those skilled in the art.

The function of the relay S³ is to close 105 circuit from the battery wire 15 to the wire 17, so as to supply current to the contact of the relay S', which thereafter determines whether the lamp s' shall receive current or not. When the called subscriber 110

has answered this lamp s' is cut off, remaining without current and dark throughout the connection. When the called subscriber answers it is necessary to provide against continued ringing, hence I take the tap 19 off in parallel with the lamp branch 18 and so to the relay K.

In the answering end of the cord the relays S^2 and S correspond in their functions to S^3 and S' , and since it is my desire to have the calling subscriber control ringing after the first ring, I take the wire 20 to ground through back contacts of the relay S, which are separated when the relay is energized.

It might happen that the called subscriber would hang up first, and in fact in most cases this does happen. In such case if the calling subscriber tried to make a recall by attracting the attention of the operator through flashings of the supervisory lamp s , he would ring again the subscriber with whom he had previously conversed. It is to cure this that I introduce the self-locking relay S^4 . I have stated that the relay K is made sluggish. This is not essential so long as the relay S^4 is provided, although it is preferably so in order to enable the calling subscriber to give a special signal to the operator even before the called subscriber answers. The relay S^4 is grounded on one side, and is connected to a front contact on the relay S' on the other side. When the called subscriber answers relay S' pulls up, S^4 takes current, and pulls up, one of its armatures s^2 closes a short circuit from its own winding to the wire 17, and the other one, s^3 , opens the circuit 19-190 from magnet K to the tap 18. Once attracted, the armatures of relay S^4 remain so as long as current flows through and energizes the relay S', which is as long as the calling plug P' remains in the jack J'. After the called subscriber has answered, and his supervisory relay S' has once pulled up, it is therefore impossible to energize the ringing relay K again without withdrawing the plug P', to permit the magnets S' and S^4 to release, and then reinserting it.

In Fig. 2, I have shown a cord circuit, or rather the calling portion thereof, suitable for use with party lines, showing the applicability of my invention thereto. Here the relay K has the same connections as in Fig. 1, and the cord circuit is the same, so I have omitted these. Whereas in Fig. 1, however, I have shown the generator circuit 23 containing generator G, bridged across the tip and sleeve of the plug through the armatures k' and k^2 , in ringing, in Fig. 2 I have shown a pair of bus-wires 23 and 230, extending from the ringing contacts of the relay K through four selective keys K^2 , K^3 , K^4 and K^5 , each of which is adapt-

ed to connect a particular generator in a suitable manner to ring some one of four stations on a party-line. There are numbers of ways in which this can be done, but I have chosen to indicate four generators 70 G^1 , G^2 , G^3 and G^4 , connected respectively to the contacts k^4 , k^6 , k^8 and k^{10} , while on the other side their common return is connected to all of the contacts k^3 , k^5 , k^7 and k^9 . These generators give four different frequencies.

In each figure I have shown the battery B connected through a resistance coil I or I' (which may also be a choke coil) to the sleeve side of the circuit during ringing, 80 this being necessary to hold up the cut-off relay N without permitting it to chatter.

The operation of my invention thus described is as follows: Assuming that subscriber A desires connection with subscriber 85 A', the former removes his telephone from the hook and thereupon current flowing in his line 1-2 will energize the relay M and light the line lamp. The operator perceiving the signal inserts the plug P in the jack 90 J, whereupon current flows from battery B through wire 15, relay S^2 and wire 11, conductor 7, plug and jack to the cut off relay N, which pulls up and removes the line relay M from the circuit. Current also flows over 95 the path thus traced and out over the line wire 2 through the subscriber's station, back by line wire 1, conductor 5, wire 9, relay S and wire 14 to ground. This supplies talking current, and by energizing the relay S 100 disconnects the battery wire 13 from the lamp s and the ground wire 14 from the branch wire 20. Having ascertained the number wanted and tested the line jack thereof, the operator inserts the plug P'. 105 The first effect of this is to permit current to flow from battery B by wire 15 through the relay S^3 and cord conductor 8 to the cut off relay N of the called line, which removes the line relay and signal therefrom. At the 110 same time relay S^3 puts current on wire 17 and the armature s^2 . I should here state that I have not considered it necessary to show the operator's listening key, this being of any well-known or desired type. After 115 inserting the plug, the operator may ring by pressing the button K^6 , which closes the following circuit: B, 15, 17, 18, 19, s^2 , 190, K, 21, K^6 and ground back to battery. Relay K thereupon pulls in its armatures, disconnects the plug P' from the cord conductors 120 6 and 8, and connects it to the generator circuit 23 and on the sleeve side through coil I to the battery. Upon releasing the key K^6 the relay K lets go and re-completes the 125 talking circuit, and thereafter if the called subscriber does not immediately answer, further ringing may be done in any one of three ways, viz., by the operator again depressing key K^6 ; by the subscriber moving 130

his switch hook up and down somewhat slowly at the calling station A; or by the automatic commutator controller K⁶. Strictly speaking, these are not alternatives, 5 nor are they intended to be used all at once. The operator's key K⁹ I have shown permanently connected, as the operator should always have control if she desires to exercise it; but the other two operating means I 10 have shown provided with switches m, m', whereby either or both may be disconnected, in the latter case the operator retaining sole control, as at present.

The commutator K⁶ grounds the magnet K for a specific period of any desired duration, and then takes off the ground for a certain period, thus intermittently exciting the relay K and ringing the subscriber A' at intervals. This ringing means may well be 15 employed during rush hours, and the operator may then abandon the use of her manual key entirely, simply inserting the plug P' and leaving the commutator to do the rest. This would be most desirable during the 20 busy hour in the business district, where calls are answered with promptness, and the calling subscriber does not wish to do anything himself, finding even that waiting without working is too much of a tax on his patience. 25 The switch m' being opened, and the switch m closed, control of the ringing is now given to the calling subscriber. All subscribers are informed that after they have initiated a call and a connection, they can actually ring up 30 the party wanted by moving the hook up and down somewhat slowly. The makes and breaks thus produced in the circuit 35 1—2 cause the relay S to become intermittently energized, making and breaking the contacts connected to the lamp s and to the ringing wire 20, by the following circuits: for the lamp, B, 15, 13, s and ground; for ringing, B, 15, 17, 19, s³, 190, K, 22, 20 and ground. If the oscillations are very rapid 40 45 the subscriber will as rapidly flash the lamp s, even if relay K is made quick, the operator then understanding that the subscriber wants her alone.

On a recall, after the conversation has 50 been finished and before plug P' has been removed, the lamp s can again be flashed, as usual, without ringing. No matter what the means of control for the ringing, when subscriber A' answers by taking down his receiver he completes a path for current from 55 the main battery B over his line through the supervisory relay S'. When this relay pulls up it cuts off the wire 19 as well as the lamp s' from the battery wire 17, and connects the latter through wire 16 to the relay S⁴, which 60 in turn pulls up, and while armature s² breaks the wire connection 19—190, the armature s² closes from 17 direct to the winding of S⁴, making the relay self-locking, removing it from the further control of relay S',

and placing it under the control of S³, that is locking it up until the plug P' is actually withdrawn for a greater or less period from the jack J'. The circuit of relay K being thus permanently broken when the called 70 subscriber answers, the hanging up of his receiver may be followed by an immediate recall due to the calling subscriber moving his switch hook up and down, to flash the lamp s, without ringing. The operator perceiving 75 this lamp flash and the other lamp s' to burn steadily, will at once withdraw the plug P' and come in on her listening key ready to make another connection without withdrawing the plug P. As soon as the plug P' is 80 pulled, the relay S³ loses current, lets go its armature, and the self-locking relay S⁴ also then lets go, even though the armature of S' is back. The circuit of magnet K is thus restored, and the magnet S⁴ is again placed 85 under the control of relay S'.

Referring to Fig. 2, the operation in ringing a subscriber on a party-line is the same as that described in the foregoing, except that the operator after inserting the plug P' 90 depresses one of the keys K², K³, K⁴ or K⁵, corresponding to the station wanted. This connects a generator to give suitable current to ring the bell at that station. Each of these keys remains down when depressed, 95 leaving its generator on the terminals 23—230. For repeated ringing therefore the same generator will again be connected each time unless another key is depressed. This saves the operator even in manual ringing 100 the trouble of finding the key used before.

I have described my invention as applied to a two wire cord of the so-called four-relay type. Obviously however, it is not limited to that type or to two wires. The prime requisites upon which it depends are the supervisory relays S, S', which are found in almost every system. A secondary requisite is found in the relays S², S³, or their equivalent. These relays merely cut off battery from the lamps in the cord when the latter is idle; and they may be and frequently are replaced by plug seat switches, by third conductors in the cord and third contacts on 110 the plugs coöperating with the sleeves of the jacks, or the like. In Fig. 3 herewith I have illustrated the first of these modifications. In this figure the general circuit is the same as that of Fig. 1, but the wire 17 is shown 115 removed from control of the relay S³, and connected to the battery wire 15 through a plug seat switch P² of the type illustrated and described in U. S. Letters Patent No. 507,983, November 7, 1893, to O. A. Bell. 120 This is so arranged that when a plug P' is idle and resting in its seat, the battery connection between 15 and 17 is maintained open at the contacts p', p². As to the second modification, an arrangement employ- 125 130

ing a third conductor with coöperating jack and plug contacts for a similar purpose is shown and described in U. S. Letters Patent No. 564,328, July 24, 1896, to W. W. Dean.

5 I have described my invention as applied to subscribers' lines direct; but it is particularly applicable to trunk line ringing.

Having thus described my invention what I claim and desire to secure by Letters 10 Patent is:

1. In a telephone exchange system, a calling and a called subscriber's line, with an operator's cord-circuit to interconnect them; a ringing generator and means to connect 15 it to the called line only, magnetic means for actuating said connecting means adapted to be controlled by the calling subscriber, and other means independent thereof for disabling the connecting means, controlled 20 by the called subscriber, substantially as described.

2. In a telephone exchange system, a calling and a called line, and a cord-circuit for interconnecting them comprising an answering and a calling plug and cord conductors inductively divided; a supervisory relay connected with the answering end of the cord to be controlled by the calling subscriber, a second supervisory relay connected with the 25 calling end of the cord and controllable by the called subscriber, a ringing relay associated with the calling plug and a suitable source or sources of current adapted to be connected thereby, means controlled by the 30 answering supervisory relay as determined by the calling subscriber, for actuating the ringing relay, and means controlled by the calling supervisory relay as determined by the called subscriber for permitting or preventing the 35 actuation of said ringing relay, substantially as described.

3. In a telephone exchange system, subscribers' lines, a common battery for supplying current thereto and a connective circuit comprising the following instrumentalities: an answering and a calling plug, cord conductors connecting the same and inductively divided; a pair of supervisory relays connected respectively with the answering and 40 the calling end of the cord, a ringing relay and a generator, a supervisory signal in a circuit controlled by each supervisory relay, and means for rendering said circuits operative when the plugs are inserted, a ringing 45 relay circuit also controlled by said means and closed when the calling plug is inserted, a disabling relay having contacts controlling said ringing relay circuit and itself controlled by contacts in the calling 50 link relay, together with controlling contacts for the ringing relay circuit in the answering link relay, and means whereby the disabling relay after being energized will remain energized until the calling link terminal is disconnected, substantially as described.

55 60 65

4. In a telephone exchange system, a calling and a called subscriber's line, with a link circuit having switching terminals to interconnect them, a ringing generator and means to connect it to the called line only, magnetic means for actuating said connecting means, adapted to be controlled by the calling subscriber, and other means independent thereof for disabling the connecting means, controlled by the called subscriber, substantially as described. 75

5. In a telephone exchange system, a calling and a called line, and a link circuit for interconnecting them comprising an answering and a calling switch terminal and connecting conductors inductively divided; a supervisory relay connected with the answering end of the link to be controlled by the calling subscriber, a second supervisory relay connected with the calling end of the link and controllable by the called subscriber, a link relay associated with the calling terminal and a suitable source or sources of current adapted to be connected thereby, means controlled by the answering supervisory relay as determined by the calling subscriber, for actuating the ringing relay, and means controlled by the calling supervisory relay as determined by the called subscriber for permitting or preventing the 95 actuation of said ringing relay, substantially as described. 90

6. In a telephone exchange system, subscribers' lines, a common battery for supplying current thereto and a connective circuit comprising the following instrumentalities: answering and calling switching terminals, link conductors connecting the same and inductively divided, a pair of relays connected respectively with the answering and calling end of the link, a ringing relay and a generator, supervising circuits controlled by each of said relays, and means for rendering said circuits operative when the link terminals are connected, a ringing relay circuit also controlled by said means and closed when the calling switching terminal is connected, a disabling relay having contacts controlling said ringing relay circuit and itself controlled by contacts in the calling link relay, together with controlling contacts for the ringing relay circuit in the answering link relay, and means whereby the disabling relay after being energized will remain energized until the calling link terminal is disconnected, substantially as described. 100 105 110 115 120

7. In a telephone exchange system, a calling and a called subscriber's line, with a link circuit having switching terminals to interconnect them, a ringing generator and means to connect it to the called line only in making a connection, means adapted to intermittently actuate said generator connecting means, a device actuated in com- 125 130

pleting the connection for placing said generator connecting means under control of the calling subscriber, and mechanism controlled by the called subscriber and operable in the intervals of actuation only to disable said generator connecting means, substantially as described.

8. In a telephone exchange system, a subscriber's line and signal receiving apparatus, together with means at another station for making connection with said line; means under control of the calling subscriber for applying calling current at intervals to the called subscriber's line after they are connected, and other means controlled by the subscriber and operable in non-calling intervals only for disabling said means for applying the calling current, substantially as described.

9. In a telephone exchange system, subscribers' lines, a common battery for said lines, a link circuit and calling means comprising the following instrumentalities: an answering and a calling switch terminal, a magnetically controlled ringing relay, a periodic circuit-closer for said relay, another relay associated with the answering link terminal and controlled by a calling subscriber to open and close the circuit of the ringing relay, and still another relay associated with the calling link terminal and controllable by a called subscriber in the intervals of ringing, to disable or prevent the further actuation of said ringing relay, at will; all as and for the purpose intended, substantially as described.

10. In a telephone exchange system, the combination with a central exchange, of substations connected therewith through telephone lines, a cord circuit at the central exchange, a source of ringing current at the central exchange normally disconnected from the cord circuit, a relay controlling the connection of said source with the cord circuit, a second relay controlling the circuit for said first relay, and interrupter means in said circuit for periodically causing closure of said circuit to periodically cause action of the first relay to connect the source with the cord circuit and with a line connected therewith.

11. In a telephone exchange system, subscribers' lines, a common battery for said lines, and a connecting cord circuit and calling means comprising the following instrumentalities: an answering and a calling plug,

a ringing relay, a periodic circuit closer connected to the windings of said relay on one side, a calling supervisory relay connected to the calling plug, normally closed contacts on said relay connected to the ringing relay on its other side, a battery supply circuit for said supervisory relay contacts, a pair of contacts included in said battery circuit and directly opened and closed by the calling plug, when making and breaking connection with the wanted line.

12. In a telephone exchange system, subscribers' lines, a common battery for said lines, and a connecting cord circuit and calling means comprising the following instrumentalities: an answering and a calling plug, a ringing relay, a periodic circuit closer connected to the windings of said relay on one side, a calling supervisory relay connected to the calling plug, normally closed contacts on said relay connected to the ringing relay on its other side, a battery supply circuit for said supervisory relay contacts, a pair of contacts included in said battery circuit and directly opened and closed by the calling plug, when making and breaking connection with the wanted line, together with a self-locking cut-off relay having its windings connected to a normally open contact on said supervisory relay adapted to be closed on the battery supply circuit when the ringing relay circuit is disconnected therefrom, a pair of normally closed contacts in said cut-off relay connected serially in the circuit of the ringing relay, and a connection from the locking contact of said cut-off relay direct to the battery supply circuit leading through the plug control circuits, whereby ringing will proceed forthwith when the calling plug is lifted from its seat and inserted in the wanted line jack, and when the subscriber answers the ringing relay will be cut off, the locking relay energized, and ringing back thereby positively prevented by the continued energization of the locking relay until the calling plug shall have been removed from the wanted line jack and returned to its normal or inoperative condition.

In testimony whereof I have affixed my signature in presence of two witnesses.

EDWARD E. CLEMENT.
